UNITED STATES PATENT OFFICE.

CORNELIUS ARTHUR RYERSON, OF TORONTO, ONTARIO, CANADA.

FUEL-SAVING ATTACHMENT FOR FURNACES.

1,369,841.

Specification of Letters Patent.

Patented Mar. 1, 1921.

Application filed November 1, 1919. Serial No. 335,037.

To all whom it may concern:

Be it known that I, CORNELIUS A. RYERSON, of the city of Toronto, in the county of York, Province of Ontario, Canada, have 5 invented certain new and useful Improvements in Fuel-Saving Attachments for Furnaces, of which the following is a specification.

This invention relates particularly to devices adapted for use in connection with hot air furnaces to check and steady the draft and effect a saving in fuel, and my object is to provide a device for this purpose which is easily constructed of a minimum amount 15 of material, which will occupy a minimum amount of space, and which is readily arranged so that the inlet and outlet pipes thereof may be at different levels and at different angles to one another.

20 I attain my object by means of the constructions hereinafter described and illustrated in the accompanying drawings in which—

Figure 1 is a vertical section of a fuel saving attachment constructed in accordance with my invention;

Fig. 2 a similar view showing a slight modification of the same; and

Fig. 3 a cross section through the form 30 shown in Fig. 1.

In the drawings like numerals of reference indicate corresponding parts in the different figures.

1 is a closed cylinder of sheet metal set 35 substantially vertical. Through the opening in the top of this cylinder depends the smoke pipe 2, which extends down to a point a short distance above the bottom of the cylinder 1. With the upper end of this pipe 40 communicates a smoke inlet pipe 3 and the smoke outlet pipe 4. These two pipes may be in axial alignment as shown in Fig. 1, or one may extend laterally from the upper end of the smoke pipe 2 and the other from 45 the top thereof as shown in Fig. 2, though various other arrangements are of course possible.

Extending from the side of the cylinder 1 near the top up to the smoke outlet pipe 4 50 is the smoke pipe 5. This may either extend diagonally as shown in Fig. 1 or may be an elbow as shown in Fig. 2. A damper 6 of any ordinary type is located in the smoke outlet pipe between its point of connection 55 with the pipe 2 and its point of connection

with the pipe 5. When this damper 6 is closed, the products of combustion arriving through the smoke inlet pipe 3 pass down the pipe 2, up through the annular space between this pipe and the cylinder and through 60 the pipe 5 to the smoke outlet pipe.

It is sometimes desirable to completely cut off the pipe 2 from connection with the inlet and outlet pipes when the damper 6 is opened. For this purpose I provide in the 65 pipe 2 close to its upper end a damper 7 by means of which this object may be attained. Loss of draft due to eddying in the lower part of the device which would otherwise occur is thus entirely avoided. To control 70 the draft of the furnace it is preferable to use a damper as close to the furnace as possible. For this purpose I provide a damper 16 in the pipe 3. The device will however work to some advantage without either of 75 the dampers 7 and 16. A clean out door 8 may be provided in the side of the cylinder at the bottom as shown in Fig. 2, though I prefer to provide the clean out opening in the bottom of the cylinder and to close it 80 by means of the cap 9 (see Fig. 1) telescoping over a flange surrounding the clean out opening.

Air to lighten the heavy products of combustion or to ventilate the apartment in 85 which the device is located may be admitted through a pipe 10 which, when in position, extends up within the lower end of the smoke pipe 2 and preferably has a baffle or cap supported above its other end. This 90 cap may communicate with an opening in the bottom of the cylinder controlled by a damper 12 as shown in Fig. 2. It may also be connected with the cap 9 as shown in Fig. 1, the opening into the pipe 10 in this case 95 being in the bottom of the cap.

For some purposes it is desirable to allow cold air to enter the upper part of the cylinder and I therefore provide the slide damper 13 for this purpose. If desired, a ring-shaped sliding damper 14 may also be provided in the pipe 5 as shown in Fig. 1.

I also find that this device may be employed to heat water for domestic purposes and for that purpose I provide one of the 105 depending parts, for instance the pipe 2, with a water jacket 13 (see Fig. 1). Suitable inlet and outlet pipes 14 and 15 communicate with this jacket. It is also desirable to be able to vary the length of the circuitous 110

path through which the products of combustion travel to suit different furnaces or different conditions of draft. I therefore prefer to make the cylinder 1 and the pipe 2 telescopic with sleeved extensions 1^a and 2^a. These extensions will usually hold in place by friction but bolts 17 may be employed if desired.

What I claim as my invention is:—

- 10 1. A fuel saving attachment for furnaces comprising a closed cylinder; a smoke pipe extending down through the upper end of the cylinder to a point a short distance above the bottom; a smoke inlet pipe communicating with the upper end of the pipe; a laterally extending smoke outlet pipe communicating with the upper end of the depending pipe; a smoke pipe extending from the side of the cylinder near the top to the laterally extending pipe; and a damper in the laterally extending pipe between its point of communication with the depending pipe and its point of communication with the pipe leading from the side of the cylinder.
- 15 2. A fuel saving device constructed as set forth in claim 1 in which an air inlet pipe
- 20
- 25

extends through the bottom of the cylinder part way up the depending pipe.

3. A fuel saving device constructed as set forth in claim 1 in which an air inlet pipe 30 extends through the bottom of the cylinder part way up the depending pipe, and a conical baffle located above the upper end of the air pipe.

4. A fuel saving attachment for furnaces 35 comprising a closed cylinder; a smoke pipe concentric with the cylinder extending down through the cylinder to a point a short distance above the bottom; a smoke inlet pipe communicating with the upper end of the 40 depending pipe; a smoke outlet pipe communicating with the interior of the cylinder; and damper controlled communications whereby the products of combustion arriving through the smoke inlet pipe may be 45 directed down the depending pipe or allowed to pass substantially directly to the smoke outlet pipe.

Signed at Toronto, Canada, this fifteenth day of October, 1919.

CORNELIUS ARTHUR RYERSON.
